TELEPHONE SYSTEM

Application filed December 10, 1928. Serial No. 324,816.

This invention relates in general to automatic telephone systems, more particularly to such systems in which finder switch mechanisms are employed to connect an idle trunk line with a calling line, and the principal object of the invention, briefly stated, is the production of a new and improved finder switch system, the improvements permitting lessened manufacturing and maintenance costs without impairing reliability or efficiency of the system.

Finder switch systems devised heretofore have employed one or two relays for each line in the system, these relays being individual to the line and permanently associated with it. When the line initiates a call one of the relays operates to start the finder switch mechanism to establish a connection with the line. When the connection is established the other relay is operated to cut off the first relay and clear the line to permit switch operation and conversation. A relay is not an expensive device but when a relay is employed for each line, a large number of such relays are required in a system of any size, those relays representing an appreciable part of the total cost of the system. It is to the lessening of the cost of the system by the elimination of the individual line relays, that this present invention is directed.

In my copending applications Serial No. 120,547, filed July 6, 1926, and Serial No. 229,018, filed October 27, 1927, I disclose a finder switch system in which there are no individual line or cut-off relays. Instead of using the customary relays I employ a constantly moving line equipment thru the operation of which a 25 or 50 point finder switch is operated to establish a connection with a calling line. The present invention has for its principal object the improvement of the system of my co-pending applications by adapting it for use in a larger telephone system wherein finder switches are of larger capacity.

As an object of my invention I provide a constantly moving line equipment of 100 line capacity together with 100 point finder switches and circuit arrangements enabling the line equipment to control the finders

through two motions to establish a connection with a calling line.

Further objects of my invention not specifically mentioned here will be best understood from a detailed reading of the description and claims which follow.

The drawings comprising Figs. 1 and 2, when laid with Fig. 2 to the right of Fig. 1 with correspondingly numbered lines in alignment, show by the usual circuit symbols sufficient details to enable a clear understanding of my invention.

In Fig. 1 I show the substation A and the details of the bank assembly of the line equipment. This line equipment, which may be of the type shown in my copending application Serial No. 229,018, filed Oct. 27, 1927, comprises five sets of wipers which are constantly moving over a semi-circular set of contacts, there being a contact group for each of the wipers in each of the sets. Each wiper has access to 22 contacts, those contacts being associated with 20 lines. By this arrangement, the group of 100 lines is periodically tested by the rotating wipers and a calling one of the lines is answered by the momentary association of auxiliary relays with it through the wipers having access to that particular line.

In Fig. 2 I show finder F which is a well known Strowger two motion finder switch whose wipers move first in a vertical direction to select a level containing a calling line and then in a horizontal direction to select a particular line in the level. In the present circuits the movements of the wipers are controlled solely by the control equipment, that is there are no testing functions performed through the wipers until after they have been set upon a particular contact set. The finders F are preselected for use one at a time by distributor D, which is a switch mechanism similar to the well known rotary line switch whose wipers have no normal position but are moved one step forward upon each de-energization of the magnet. Associated with the distributor D are the relays 18 to 23, inclusive, through the operation of which the setting of the finder switch F is con-

trolled after the calling line has been found by the line equipment.

Fig. 2 also shows the relays 1 to 11, inclusive, which are divided into five groups, 6 one for each set of wipers of the line equipment. Relays 1 and 2 are associated with the wipers 30 to 34 inclusive of the first line equipment, the relay 2 being a line relay which is thrown across the subscriber's loop 10 and energized if that group is shorted, that is if the receiver is off the hook. Relay 1 is a cut-off relay which is energized each time the private wiper P1 encounters the contacts of a busy line, in a manner which will be 15 pointed out in detail hereinafter.

Similarly relays 3 and 4 are associated with the wipers 35 to 38, relays 5 and 7 with the wipers 39 to 42, relays 8 and 9 with the wipers 43 to 46, and relays 10 and 11 with 20 wipers 47 to 50. Relay 5 is common to the entire group of line equipments, and is energized when one of the equipments is taken into use to disconnect the private wipers P1, P2, P3, P4, and P5 from their respective cut-off 25 relays to prevent energization of those cut-off relays until the finder then being operated is completely set.

Referring now to Fig. 1 in more detail it will be noted that the wipers 30 to 34, inclusive, have access to lines 01, 91, 81, 71, 61, 51, 41, 31, 21 and 11, and also the lines 02, 92, 82, 72, 62, 52, 42, 32, 22 and 12. In other words these wipers have access to lines 1 and 2 in each of the ten levels in the banks of 35 the Strowger finder switch. It will be also noted that wipers 35 to 38, inclusive, have access to lines 3 and 4 in each of the ten levels of the finder switch bank and that wipers 39 to 42 have access to lines 5 and 6 in each of 40 the levels. Wipers 43—46 have access to lines 7 and 8 in each of the ten levels and wipers 47 to 50, inclusive, have access to lines 9 and 10 in each of the ten levels. This arrangement splits up the grouping of the 45 lines so as to permit the control equipment to control both the vertical and rotary motion of the finder switch, the control equipment taking not more than one half of a revolution, that is the wipers are moved over 50 the 22 contacts available to them during the complete operation of the finder switch. Wiper group 1 comprising wipers 30 to 34, inclusive, contains five wipers, designated as the positive line, negative line, private, the 55 vertical wiper, and the B wiper. The two line wipers positive and negative and the private wiper need no detailed explanation since their function is the same as similarly named wipers in any well known Strowger 60 automatic telephone system. The vertical or V wiper is the wiper through which the vertical movement of the finder switch is controlled and the B wiper is the wiper through which the rotary movement of the 65 finder is controlled. Since the vertical

designation of all lines in the group is the same the line equipment #1 comprising wipers 30 to 34, inclusive, is the only equipment containing a V or vertical wiper and the remaining equipment sets contain but four wipers, the positive and negative lines and private and the B wipers.

In order to enable an understanding of the system it will be assumed that line 75 initiates a call and that the wipers 30 to 50 rotating from left to right encounter the contacts to which the line A is connected. The line relay associated with the wipers 39 and 40 will have its circuit closed through the hook switch and instrumentalities of the substation A, and finder F, which has been pre-selected by distributor D will be started in search of the calling line. At the same time that wipers 39 and 40 are engaging contact 75 wiper 33 is engaging contact *a*. Responsive to the energization of the line relay associated with these wipers a circuit is completed through the vertical wiper 33 and contact *a* to the vertical magnet of the finder F, to energize that magnet to elevate the shaft 80 of the finder one vertical step. Wipers 30 to 50, inclusive, move on to the right at a uniform rate of speed. As the wiper 33 passes from contact *a* to contact *b* the circuit of the vertical magnet of the finder F is 85 opened to permit that magnet to fall back preparatory to taking another step. When the wiper 33 engages contact *b* the circuit of the vertical magnet of the finder is again closed and the shaft elevated another step 90 vertically. The operation continues until wiper 33 engages contact 120 at which time the vertical magnet of the finder F has received seven impulses, and the shaft is standing opposite the seventh level of the switch bank. When contact 120 is reached a circuit 95 is completed through the wiper 33 to operate the change-over relay in the control equipment, thereby opening the circuit of the vertical magnet and closing a circuit to the rotary magnet of the finder F. As the wipers 100 of the control equipment move forward wiper 42 which is the B wiper of the line equipment having access to the calling line A will complete a circuit through contact *h* to the rotary magnet of the finder F to energize that magnet to advance the wipers of the 105 finder one step in a rotary direction. When wiper 42 moves from contact *h* to *i* the circuit of the rotary magnet is momentarily opened and again closed when the contact *i* is engaged. In this manner the rotary impulsing 110 continues until the wiper 42 engages contact 127 at which time five impulses have been delivered to the rotary magnet and the wipers 115 of the finder switch F are standing opposite the fifth contact set in the selected level, that is, opposite the fifth contact set in the seventh level and are in a position to establish a connection to line 75. When contact 127 is 120

reached wiper 42 completes a circuit for the switch-through relay of the finder operating it to establish a connection with the selected line. The operation of the switch-through relay of the finder controls the distributor 5 D to step off of the contacts leading to the finder F and to start it in search of another finder in that group, preselecting that finder and preparing circuits through which it will be controlled responsive to the initiation of 10 the next call in the line group.

From the foregoing description it will be seen that the vertical movement of the finder is controlled by the number of steps that the 15 wiper 33 takes before it encounters the contacts 120 or 121. The number of steps taken by the finder in a rotary direction depends upon the B wiper used by the control equipment, and the number of steps that wiper takes after the line is found and before it 20 encounters the switch-through contacts. It will be seen that it is necessary to provide a pair of switch-through contacts for each of the five B wipers, contacts 123 and 122 operating with wiper 34 to control the rotary 25 movement of the finder when the first group of switches of the control equipment is in use. When a call is picked up in the first half of the bank, that is odd-numbered lines, 30 wiper 34 encounters one contact prior to the encountering of contact 123, wiper 38 encounters three contacts prior to 125, wiper 42 five contacts prior to contact 127, and wiper 46 seven contacts prior to contact 129, and wiper 35 50 nine contacts prior to contact 131. When a call is picked up in the second half of the banks of the control equipment, that is a call from an even-numbered line, wiper 34 encounters two contacts before the switch-through contact 122 is reached, wiper 38 four contacts, wiper 42 six contacts, wiper 46 eight contacts, and 50 ten contacts. It will be noted 40 that the controlling of the vertical movement of the finder is by the wiper 33 regardless of the control equipment handling the call, and that the B wipers control the rotary movement of the finder through the opposite half of the bank from that containing the contacts of the calling line. The reason for this 45 will be apparent when it is remembered that the line equipment comprising wipers 30 to 50, inclusive, is constantly moving and does not change its pace or stop during the setting of a call.

55 When a calling line is found, as the line 75 was found by the wipers 39 and 40, the control equipment for the entire 100 line group is momentarily made individual to that line and any other calls in the line group which 60 may be waiting will be delayed until the first call is completed and the finder establishes a connection to it. When the finder establishes this connection the distributor D is stepped off of the contacts leading to that finder. The distributor then acts as a selector picking

out the next idle finder in the group. As soon as this idle finder is found, the line equipment is restored to normal and the next calling line encountered by the wipers is answered and a finder directed to it. 70

In case of simultaneous calls on line 75 and line 79, for example, the line of the lower units designation will be answered first notwithstanding that the line relays of two of the controlling equipments are simultaneously 75 engaging the contacts of a calling line. The locking circuit for the line relays 2, 4, 7, 9 and 11 extends through chain contacts on these relays themselves, that chain being broken by the relay nearest to relay 18, 80 which terminates the chain, to cut off the other line relays. When line relays 7 and 11 are simultaneously energized by their respective wipers encountering contacts of a calling line, relay 7 will be locked energized and 85 relay 11 will be deenergized as soon as wipers 47 and 48 leave the line contacts since the locking circuit will be opened by springs 73 of relay 7.

Having just described my invention in general, I will now proceed with a detailed description of its operation. 90

Busy guarding

The wipers 30 to 50 of the line equipment 95 are constantly moving from the left hand side to the right hand side of the bank contacts pictured in Fig. 1, the equipment for doing this being shown in my co-pending application Serial No. 229,018, filed October 2, 1927. 100 Unless special provisions were made to prevent the interference of this equipment with the lines in the group which are already in use, subscribers talking over that line would hear a series of clicks each time the positive 105 and negative line wipers of the group encounter the contacts of a line. To guard against this, I have provided cut-off relays 1, 3, 6, 8 and 10, each associated with one of the private wipers P1, P2, P3, P4, and P5 110 which wipers engage the private contacts of the lines in the bank. The private contacts in the bank are spaced a little in advance of the other contacts of the set. If a line has been taken for use in a finder switch ground 115 is placed on to the private wiper 52 by the spring 93 of the switch through relay 14 of the finder to extend a circuit through that wiper and the private contact and release 120 trunk engaged thereby, to the P contact in the bank of the line equipment associated with that line. When the private wiper of the line equipment having access to that line, 125 encounters this P contact this ground completes a circuit through the wiper, 41 for example, through contacts 72, through the cut-off relay 6 to battery, to energize that relay which at springs 70 and 71 removes ground and battery from the line wipers 39 and 40. Since the private contact P is in advance of 130

the line contacts relay 6 will be energized before the line wiper engages their contacts and there will be no click in the line when these wipers engage since they are connected to nothing and do not bridge from one contact set to another. If the line 75 happens to be taken for use by the connector the private contacts CP in the bank of the connector will be grounded by that switch and circuit of the cut-off relay 6 will be closed as before. Thus it will be seen that lines already in use will not be interfered with in any way by the passing of the line equipment wipers over their contacts.

15 Line A initiates a call

Assume now that the line A initiates a call by removing the receiver from the switch hook to complete a circuit through the telephone to the line conductors leading to the line equipment. It will be noted that these line conductors terminate only in bank contacts, those contacts being in the banks of the finder switches, the banks of the connector 20 and the banks of the line equipment. When the line initiates a call nothing occurs immediately unless the wipers of the control equipment happen to be standing on the contacts of that line at the instant. Since each 25 wiper has access to twenty contacts it will happen more often that the wipers will be elsewhere when the line initiates a call. When the wipers engage the contact set of the calling line, no circuit is closed through the 30 private contact, since that contact is as yet ungrounded. However, as soon as the line wipers engage the contacts of the line 75 a circuit may be traced from ground through springs 70, positive line L3 and the wiper 39, 35 contact 75 in the bank accessible to the wiper 39 to the subscriber's loop and telephone, the negative line contact in the bank, wiper 40 engaging that contact, the negative line L3 connected thereto, springs 71, through the 40 upper winding of relay 7 to battery. Relay 7 energizes over this circuit and at spring 73 breaks a point in the locking chain of the succeeding line relays and locks itself from battery through its lower winding, spring 73 45 and its make contact, spring 68 and its break contact, spring 63 and its break contact, through the winding of relay 18 through the break contact of spring 100 to ground. Relay 18 energizes in this circuit and relay 7 is 50 locked in its energized position.

The energization of relay 18 at springs 99 closes the obvious circuit through the winding of relay 21 of the distributor equipment D, to energize that relay for a purpose which 55 will be hereinafter pointed out. At springs 98 relay 18 closes a circuit from ground through multiple paths, the one leading through the lower winding of relay 10 the lower winding of relay 8, and the winding of relay 5 in series to battery, to energize relays 5, 8 and

10. The other multiplied path leads through the lower winding of relay 6, the lower winding of relay 3 and the lower winding of relay 1 to battery to energize relays 1, 3 and 6. It will be seen that responsive to the energization of relay 7, relays 18, 21, 1, 3, 5, 6, 8 and 10 have all been energized.

Relay 5 at the springs controlled by it opens the private wipers of the line equipment so that no further tests are made by the distributor and line equipment during the setting of the present call. Relays 1, 3, 6, 8 and 10 are energized to remove the ground and battery connections from the positive and negative line wipers of the line equipment so that lines which may be in use will not be interfered with while the private wiper circuits are disabled. Relay 7 being locked independently of the springs 70 and 71 will not fall back at the moment.

The energization of relay 21 prepares a locking circuit for the relays 19, 20 and 22 by closing springs 106; and prepares a point in the circuit of the distributor motor magnet 24 by closing springs 105. At springs 104, relay 21, closes a circuit from ground through wiper 55, through the winding of relay 13 to battery. Relay 13 energizes over this circuit to open a point in the finder release circuit at springs 87 and to prepare 95 points in the finder switch through circuits at springs 88 and 92.

Vertical impulsing

The finder switch F, having been pre-selected by the distributor D in a manner which will be hereinafter pointed out, is now operated in a vertical direction a number of steps corresponding to the number of contacts engaged by the wiper 33 prior to its arrival at a cut-off contact. When relay 18 energizes a circuit is closed from ground through springs 97 and the vertical impulse conductor V, wiper 33, contact a, which is in line with the line contacts 75 from which the instant call is initiated, and therefore simultaneously engaged by the wipers, vertical interrupter conductor 142, and thence over parallel paths, the one through springs 110, through the winding of relay 23 to battery, 110 and the other through spring 111, wiper 57, through the winding of the vertical magnet 16 to battery. Relay 23 energizes over this circuit, locking itself over a circuit traceable from ground through springs 96, springs 95, wiper 56, springs 112, through the winding of relay 23 to battery.

The vertical magnet 16 energizes over the above circuit, and is locked energized independently over the wiper 33, over the circuit just traced from the wiper 56 to springs 112, thence through springs 110 and 111, through the previously traced path to the vertical magnet 16. When the vertical magnet 16 is fully energized the locking path of that mag- 130

net and the relay 23 is broken and if the wiper 33 has passed off to the contact *a* that relay and magnet will fall back. When the magnet 16 energizes it advances the shaft, not shown, carrying the wipers 51 to 53 one vertical step, in which position the wipers are held by the well known mechanical attachments on the switch. As the line equipment and wiper 33 move forward contacts *b*, *c*, *d*, *e*, *f*, and *g* are encountered in turn and six more impulses are sent over the circuit just traced to the vertical magnet. The magnet is operated seven times to elevate the wipers 51 to 53 seven steps in the vertical direction, in which position they are standing opposite the seventh level of their banks.

Change over

When the wiper 33 encounters change-over contact 120 it closes a circuit from grounded spring 97, through the change-over conductor 143, through the winding of relay 22 to battery, energizing that relay which locks itself through the springs 106 and 108. The energization of relay 22 opens the circuit of the vertical magnet 16 of the finder at springs 111, and closes a circuit from the rotary interrupter conductor 140 through the winding of relay 23. At springs 109 relay 22 closes a circuit from ground through spring 74 and the conductor B3 to the wiper 42 which is now in engagement with contact *h* of the bank. This circuit extends through the contact and the rotary interrupter conductor and thence over parallel paths, the one through conductor 140, through spring 103 and the winding of relay 20 to battery, the second through spring 110 and the winding of relay 23 to battery, and the third through conductor 144, wiper 58 and the rotary magnet 17 to battery. Relay 20 upon energizing locks itself through springs 103 and 106 to ground, and at springs 102 prepares a point in the switch-through circuit of the finder. Relay 23 energizes as before and at spring 112 locks itself to ground through the interrupter springs 95 and 96 of the finder F, this ground circuit also extending through springs 112 and 110 to the junction of the conductors 140 and 144 to lock the rotary magnet circuit independently of the wiper 42 so that the rotary magnet is insured of full operation. When the wiper 42 passes off of contact 8 relay 23 falls back if the rotary magnet has been fully energized and the rotary magnet falls back to complete its first step, which step has rotated the shaft, not shown, carrying wipers 51 to 53, inclusive, one step in the rotary direction to bring the wipers into engagement with the first bank contacts in the seventh level of their banks. Impulses are transmitted in this manner to the rotary magnet and relay 23 when wiper 42 encountered contacts *h*, *i*, *j*, *k*, and *l*, a total of five impulses delivered to

the magnet to bring the wipers of the switch to the fifth contact set in the seventh level.

Switch through

When wiper 42 encounters switch-through contact 127 a circuit is closed from ground through the previously traced circuit to the wiper 42, through the switch-through conductor 141, through spring 102 and thence over parallel paths one through springs 105 and the magnet 24 of the distributor switch D to battery. The second path extends through the relay 19 to battery, and through wiper 54 and off-normal springs 86, spring 88 and its make contact, through the winding of relay 14 to battery. Relay 19 energizes over this circuit and locks itself energized through springs 101 and springs 106. At springs 100 relay 19 opens a point in the circuit of relays 18 and 7 to permit these relays to deenergize. The circuit of cut-off relays 1, 3, 5, 6, 8 and 10 is maintained closed through the make before break combination 100 so that the latter relays are not deenergized at this time. The motor magnet 24 of the distributor switch D is energized, but the wipers are not advanced since said switch is of the type of the well known rotary line switch whose wipers are advanced when the magnet deenergizes rather than when the magnet energizes.

The energization of relay 14 of the finder closes the line circuit through the wipers 51 and 53 to the calling line by the operation of springs 90 and 94. At spring 93 relay 14 applies ground through the wiper 52 and the release trunk conductor associated with the line A to protect the line from intrusion either by a connector or by the line equipment. At spring 91 the release trunk back from the selector, not shown, is extended through the relay 14 so that when the release trunk is grounded by the selector in the well known manner relay 14 is locked energized to that grounded conductor to maintain the finder in its switch-through position as long as the connection is wanted. At spring 89 relay 14 opens a point in the release circuit of the finder.

The distributor preselects an idle finder

The deenergization of relay 18 at springs 99 opens the point in the circuit of slow-to-release relay 21, which falls back after an interval and at springs 106 opens the locking circuit of relays 22, 20 and 19. At springs 105 relay 21 opens the circuit over which magnet 24 of the distributor was energized to permit that magnet to deenergize and advance the wipers of the distributor one step. If the next finder of the group happens to be idle, no further stepping is necessary, but if it is busy a circuit will be completed from ground on springs 88, off-normal springs 86, the bank contact engaged by wiper 54 through

that wiper, springs 107 and the winding of the motor magnet 24 to battery. The motor magnet is again energized and breaks its own circuit at springs 107, falling back to advance the wipers of the distributor another step. The circuit from ground on wiper 54 also extends through winding of relay 19 to maintain that relay energized so that the line equipment is not taken for use prior to the finding of an idle finder by the distributor. When an idle finder is encountered, wiper 54 loses ground and the motor magnet comes to rest deenergized. Relay 19 falls back and at spring 100 closes a point in the circuit of relay 18, to permit that relay to be operated by another call in the line group. At spring 100 and its make contact relay 19 opens the circuit through the lower windings of relay 1, 3, 5, 6, 8 and 10 to permit those relays to restore to again complete the testing circuits of the line equipment so that that equipment may look for additional calls in the line group.

While I have chosen to show my invention in connection with a particular type of apparatus, I have done so by way of example only, as there are many modifications and adaptations, which will be apparent to one skilled in the art, which can be made without departing from the spirit of the invention.

Having thus described my invention, what I consider new and desire to have protected by Letters Patent is pointed out in the appended claims.

35. What is claimed is:

1. In a telephone system, a plurality of subscribers' lines terminating in bank contacts, the contacts of said banks being arranged in groups, a finder switch having access to said lines, a constantly moving line equipment also having access to said lines, means for associating said finder with said line equipment and means in said line equipment responsive to the initiation of a call by one of said lines for directively operating said finder first to select the group containing the calling line and then to select the calling line from that group.

2. In a telephone system, a plurality of subscribers' lines terminating only in bank contacts, a two coordinate finder switch having access to said lines, and means common to said lines responsive to the initiation of a call on one of them for directing said finder through said two coordinate motions to establish a connection with said line.

3. In a telephone system, a plurality of subscribers' lines terminating in bank contacts, the contacts of said banks being arranged in groups, a two-directional finder switch having access to said groups, said finder switch having a normal position, a unidirectional constantly moving line equipment also having access to said lines, means for associating said finder with said line

equipment, and means in said line equipment responsive to the initiation of a call by one of said lines for moving said finder out of its normal position through two directions into connection with said line.

4. In a telephone system, subscribers' lines, a line equipment having a plurality of sets of wipers, a finder switch having a primary and a secondary motion, a primary test wiper in said line equipment, a secondary test wiper in each of said wiper sets, means responsive to the association of a set of said equipment wipers with a calling one of said lines for directing the primary movement of said finder switch under the control of said primary test wiper, and means controlled thru the secondary test wiper of the set associated with the calling line for directing the secondary motion of said finder to establish a connection with said line.

5. In a telephone system, subscribers' lines, a line equipment having a plurality of sets of wipers, a finder switch having a primary and a secondary motion, a primary test wiper in said line equipment, a secondary test wiper in each of said wiper sets, means responsive to the association of one set of said equipment wipers with a calling one of said lines for directing the primary movement of said finder switch under the control of said primary test wiper to operate the finder a number of steps in its primary movement dependent upon the position of the primary test wiper when said line was found calling by said set of equipment wipers, means controlled through the secondary test wiper of the set associated with the calling line for directing the motion of the finder a number of steps in its secondary movement depending on the position of that test wiper when said line was found calling by the said set of equipment wipers, and means associated with said finder for establishing a connection with said line.

6. In a telephone system, a plurality of subscribers' lines designated by tens and units digits, a line equipment having a bank of contacts and wipers sweeping over said contacts, said lines being so arranged in said bank that said wipers simultaneously test the lines of odd units designation in retrogressive order of their tens designation then test the lines of even units designation in retrogressive order of their tens designation, a finder switch having access to said lines, means in said line equipment for testing said lines for calling condition, and means responsive to the finding of such a calling line for directing said finder to it to establish a connection with it.

7. In a telephone system, a plurality of subscribers' lines designated by tens and units digits, a line equipment having a bank of contacts and wipers sweeping over said contacts, said lines being so arranged in said

- bank that said wipers simultaneously test the lines of odd units designation in retrogressive order of their tens designation then test the lines of even units designation in 5 retrogressive and of their tens designation, a finder switch having access to said lines, means in said line equipment for testing said lines for calling condition, and means responsive to the finding of two simultaneously calling lines by said line equipment for directing said finder to the one of those lines having the lower units designation.
8. In a telephone system, a group of subscribers' lines terminating in a finder switch 15 bank and in a line equipment bank, a finder switch having access to said lines, a constantly moving line equipment also having access to said lines, primary and secondary magnets in said finder, primary and secondary control wipers on said line equipment engaging auxiliary contacts associated with said lines, line wipers on said line equipment, means responsive to the picking up of an initiated call by said line wipers for extending a circuit through said primary control wiper and said primary magnet to operate the magnet a number of times dependent upon the position of said line wipers when said calling line was encountered, means operated when 20 said wipers reach a predetermined position for breaking said primary circuit and for establishing a circuit through said secondary magnet and wiper to operate that wiper and magnet a predetermined number of steps dependent upon the position of said line wipers when said calling line was encountered, means responsive to the operation of said magnets for positioning said finder upon said calling line, and means for establishing a 25 connection therewith.
9. In a telephone system, a plurality of subscribers' lines terminating in finder bank contacts in which bank they are arranged in a plurality of groups in a definite order, control equipment banks divided into a lesser number of groups of contacts to which said lines are also connected in a different order, a finder switch having wipers for registering with said finder contacts, a control equipment 30 having a wiper set for each of said groups in the control equipment bank, said wipers being moved over the contacts of their respective groups at a uniform speed, means responsive to the initiation of a call on one 35 of said lines for seizing said line equipment for the exclusive use of that call when said wipers encounter the line, and means controlled thru said line equipment wipers and dependent upon the set of wipers used and 40 the position of that set when the calling line is encountered for directing said finder to establish a connection with that line.
10. In a telephone system, a plurality of subscribers' lines, a two-coordinate finder switch 45 having bank contacts, a common line equip- ment switch having bank contacts, said lines connected to the finder bank contacts in a definite order and also connected to the bank contacts of the common switch in a different order, means for operating the common switch to seize a calling one of said lines, and means in said common switch responsive to such seizure for directing said finder switch through its two-coordinate motions in accordance with the position of the bank contacts of the said calling line in the common switch bank to establish a connection with the bank contacts of said calling line in the finder bank.
11. In a telephone system, a line equipment, subscribers' lines terminating in bank contacts in said line equipment, a finder switch having a primary and a secondary directly controlled motion for connecting with a calling line, a primary test wiper and a secondary test wiper in said line equipment, means for operating said wipers, and means responsive to the association of said wipers with the bank contacts of a calling one of said lines for thereafter directing the primary and secondary movements of the finder under control of the primary and secondary test wipers, respectively, dependent upon the position of the bank contacts of said calling line in said line equipment.
12. In a telephone system, a plurality of subscribers' lines divided into groups, a common line relay and a common cut-off relay for each group of lines, an automatic switch common to said lines and having a set of wipers for each group, means for operating said switch, means responsive to a set of said wipers encountering a calling line for energizing the line relay associated with the group in which the calling line is located, and means operated responsive to the operation of said line relay for energizing all the said cut-off relays to thereby seize said common switch for the exclusive use of the calling line.
13. In a telephone system, a plurality of subscribers' lines divided into groups, an automatic switch common to said lines and having a set of wipers for each group of lines, means for operating said common switch, means operated responsive to a set of said wipers encountering a calling one of said lines for seizing said common switch for the exclusive use of the calling line, a finder switch controlled by the operation of said common switch to establish a connection with the calling line, and means operated responsive to the establishment of said connection for causing said common switch to revert to common use for any of said lines.
14. In a telephone system, subscribers' lines, a finder switch having access to said lines, said lines divided into groups, the lines in each group comprising the same units designations and consecutive tens designations,

such designations determined by the terminating position of said lines in the finder bank, a common line relay and a common cut-off relay for each group of lines, means for associating the line and cut-off relays of each group successively with lines in their corresponding groups of lines, means responsive to the association of a line relay with a calling one of said lines for directing said finder to said line and causing it to establish a connection therewith, and means including said cut-off relays for preventing further association of said relays with said lines during the operation of said finder switch.

15. In a telephone system, a plurality of subscribers' lines, two motion directly controlled finder switches having access to said lines, an auxiliary switch for finding a line when calling, said auxiliary switch continuing to operate after connecting with the calling line, and means controlled by the continued operation of said auxiliary switch for directly operating one of said finders in its two movements to find said calling line.

16. In a telephone system, a group of telephone lines connected only to the contacts of switch banks, two-motion directly controlled finder switches having access to certain of said contacts, control equipment for said finders, a constantly moving switch for associating said control equipment with certain other of said contacts, means responsive to the association of said equipment with the contacts of a calling one of said lines for thereafter causing said constantly moving switch to generate impulses, and circuit connections over which the impulses generated by said constantly moving switch are delivered to one of said finders to directly operate it in its two movements to the contacts of said calling line.

17. In a telephone system, a group of telephone lines connected only to the contacts of switch banks, two-motion directly controlled finder switches having access to certain of said contacts, control equipment common to said finders, and a switch for connecting said control equipment with the contacts of a calling one of said lines, said switch then operating to directly control a finder in its two movements to the contacts of the calling line.

18. In a telephone system, a plurality of lines, a directly controlled two-motion automatic switch having access to said lines, a single motion auxiliary switch having access to said lines, said auxiliary switch operating to connect with one of said lines when calling, and means for causing both said switches to move together after the auxiliary switch connects with the calling line and until the automatic switch is directly operated in its two movements into connection with the calling line.

19. In a telephone system, the combina-

tion of a plurality of subscribers' lines terminating in a switch bank and having tens and units designations in accordance with the position of the bank contacts in which such lines terminate, of a second switch bank in which said lines terminate in bank contact groups each of which comprises only the bank contacts of the lines having the same units designation, and means for successively testing the lines in a group.

20. In a telephone system, the combination of a plurality of subscribers' lines terminating in a switch bank and having tens and units designations in accordance with the position of the bank contacts in which such lines terminate, of a second switch bank in which said lines terminate in bank contact groups each of which comprises only the bank contacts of the lines having the same units designation, and means for simultaneously testing all the lines in said groups having odd units designations and the same tens designation.

21. In a telephone system, the combination of a plurality of subscribers' lines terminating in a switch bank and having tens and units designations in accordance with the position of the bank contacts in which such lines terminate, of a second switch bank in which said lines terminate in bank contact groups each of which comprises only the bank contacts of the lines having the same units designation, and means for simultaneously testing all the lines in said groups having even units designations and the same tens designation.

22. In a telephone system, the combination of a plurality of subscribers' lines terminating in a switch bank and having tens and units designations in accordance with the position of the bank contacts in which such lines terminate, of a second switch bank in which said lines terminate in bank contact groups each of which comprises only the bank contacts of the lines having the same units designation, and means for consecutively testing the lines in a group in the order of their tens designations.

23. In a telephone system, the combination of a plurality of subscribers' lines terminating in a switch bank and having tens and units designations in accordance with the position of the bank contacts in which such lines terminate, of a second switch bank in which said lines terminate in bank contact groups each of which comprises only the bank contacts of the lines having the same units designation, and means for simultaneously testing a line in each of said groups, the lines in each group tested in the order of their tens designations.

24. In a telephone system, subscribers' lines designated by tens and units designations, a finder switch having a primary and a secondary controlled motion for connecting

with a calling one of said lines, said lines terminating in the bank of the finder switch in groups, each finder line group consisting of the lines having the same tens designation but different units designations arranged in a definite order, a line equipment having a bank of contacts and wipers sweeping over said contacts, said lines also terminating in the bank of the line equipment in groups, 5 each line equipment group consisting of the lines having the same units designation but different tens designations arranged in a definite order, and means responsive to the wipers of the line equipment encountering 10 the bank contacts of a calling line for operating said finder switch in its two movements to the finder bank contacts of the calling line in accordance with the position of the bank contacts of the calling line in the 15 line equipment bank.

25. In an impulse sender for directly operating a two-motion switch in a primary and then a secondary movement to complete a connection, a primary wiper, a plurality of 25 secondary wipers, means for operating said wipers, means controlled by said primary wiper for determining the number of primary impulses to be transmitted to said switch, means for selecting one of said secondary wipers, and means dependent upon 30 selected secondary wiper for determining the number of secondary impulses to be transmitted to said switch.

26. In an impulse sender for directly 35 operating a two-motion switch in a primary and then a secondary movement to complete a connection, a normally inactive primary wiper, a plurality of normally inactive secondary wipers, means for operating said 40 wipers, means for rendering said primary wiper active, means dependent upon the position of said primary wiper at the time such wiper becomes active for determining the number of primary impulses to be transmitted to said switch, means 45 for thereafter rendering only one of said secondary wipers active, and means dependent upon the selected active secondary wiper and dependent upon the position of the primary wiper at the time such wiper became active for determining the number of secondary impulses to be transmitted to said switch.

27. In an impulse sender for directly 55 operating a two-motion switch in a primary and then a secondary movement to complete a connection, a normally inactive primary wiper passing over a definite number of primary bank contacts in succession, a plurality 60 of normally inactive secondary wipers each passing over a number of secondary bank contacts, means for rendering said primary wiper active, means dependent upon the position of the primary wiper at the time such wiper becomes active for de-

termining the number of primary impulses to be transmitted to said switch, means responsive to the primary wiper engaging the last of said primary contacts for rendering only one of said secondary wipers active, and means dependent upon the selected active secondary wiper for determining the number of secondary impulses to be transmitted to said switch. 76

28. In an impulse sender for directly 75 operating a two-motion switch, a normally inactive primary wiper passing over a definite number of primary bank contacts in succession, the last of said contacts being a changeover contact for controlling the 80 changeover of said switch from its primary to its secondary motion, a plurality of normally inactive secondary wipers each passing over a number of normally inactive secondary control contacts and a normally inactive switch through contact, means for rendering said primary wiper active, means dependent upon the position of the primary wiper at the time such wiper becomes active for determining the number of primary impulses to be transmitted to said switch, means 85 responsive to the primary wiper encountering said changeover contact for rendering said secondary contacts, said switch-through contacts, and only one of said secondary 90 wipers active, and means dependent upon the selected active secondary wiper for determining the number of secondary impulses to be transmitted to said switch. 95

29. In an impulse sender, a switch bank 100 having a definite number of primary contacts, a plurality of groups of active secondary contacts, a switch-through contact associated with each group of secondary contacts, multiple connections between said primary contacts, multiple connections between said active secondary contacts, and multiple connections between said switch-through contacts, each secondary group comprising a different definite number of active secondary 105 contacts, and wipers cooperating with said contacts to control the transmission of impulses by said sender. 110

In witness whereof, I hereunto subscribe my name this 20th day of November, A. D. 115 1928.

RUDOLPH F. STEHLIK.
